UNITED STATES PATENT OFFICE.

WILLIAM GRAVIER AND M. PAYSON HUTCHINS, OF DETROIT, MICHIGAN.

DESIGN FOR A WRENCH.

45,556.

Specification for Design.

Patented Apr. 7, 1914.

Application filed April 19, 1913. Serial No. 762,412. Term of patent 7 years.

To all whom it may concern:

Be it known that we, WILLIAM GRAVIER and M. PAYSON HUTCHINS, citizens of the United States, residing at Detroit, in the county of Wayne and State of Michigan, have invented a new, original, and ornamental Design for Wrenches, of which the following is a specification, reference being had to the accompanying drawing, forming part thereof.

The figure is a plain view of a wrench showing our new design.

Our design is stamped from a sheet of suitable flat material, and has one of its ends enlarged and provided with a substantially V-shaped depression, one of the walls

formed by the depression being provided with teeth 1. The body of the wrench at the opposite sides thereof has its edges slotted, as at 2 and 3, the slot 2 being of a greater area than the slot 3, and the end of the wrench beyond the slots 2 and 3 is curved to provide the said end with a hook 4.

We claim:

The ornamental design for a wrench as shown.

WILLIAM GRAVIER.
M. PAYSON HUTCHINS.
